United States Patent Office

Des. 208,816
Patented Oct. 3, 1967

208,816

STAPLE

Altus L. Simpson, Long Beach, Calif.
(309 E. Live Oak St., Apt. F, San Gabriel, Calif. 91776)

Filed Jan. 20, 1967, Ser. No. 5,507

Term of patent 14 years

(Cl. D54—9)

FIG. 1

FIG. 2

FIG. 3

FIG. 4

FIG. 5

I claim:

The ornamental design for a staple, substantially as shown.
